BY *Albert S. Davis*
HIS ATTORNEY

UNITED STATES PATENT OFFICE.

OTIS A. MYGATT, OF NEW YORK, N. Y.

PRISM GLASS REFLECTOR FOR ARTIFICIAL LIGHTS.

1,120,963.

Specification of Letters Patent. Patented Dec. 15, 1914.

Application filed July 1, 1909. Serial No. 505,436.

To all whom it may concern:

Be it known that I, OTIS A. MYGATT, a citizen of the United States, residing at New York, in the county of New York and State of New York, have invented certain new and useful Improvements in Prism Glass Reflectors for Artificial Lights, of which the following is a specification, reference being had therein to the accompanying drawings.

The object of the invention is to produce a prismatic reflector of less weight than those now generally in use.

A further object is to provide a prismatic reflector which will expand and contract under the action of heat with less liability to break than is generally the case with prismatic reflectors previously made.

The invention consists in the following construction and disposition of the prisms, as will be more specifically described in the specification and set forth in the claims.

Figure 1 represents a plan of a reflector embodying my invention. Figs. 2 and 3 are plan views illustrative of further exemplifications of the invention. Fig. 4 is a side elevation of a modified form of reflector.

In Fig. 1 my invention is carried out by providing one surface of the reflector with a series of prisms *a* of equal width from the neck *c* to the outer edge *d*. Between equal width prisms are disposed other prisms *e* which converge between the sides of the equal width prisms *a*.

In Fig. 2 the reflector is divided into a series of panels *g* within which are disposed a series of parallel prisms *h*. The surface of the reflector in this example is divided into a plurality of panels or scales *g* which are provided with prisms *h*.

In Fig. 3 the reflector is composed of a series of converging radial prisms *k* between which are arranged a series of parallel equal size prisms *i*.

In Fig. 4 the reflector is composed of an upper series of radial panels *m* each of which is provided with parallel prisms. The lower portion of this shade is provided with an angular skirt having panels and prisms similar to those heretofore described.

In reflectors as previously constructed, and for the purposes of highest efficiency, there are generally provided radially disposed prismatic double-reflecting prisms,

such prisms being more efficient than where horizontally disposed. Such radially arranged reflectors have been open to the serious objection that the prisms have been radial converging prisms small and narrow at the neck of the reflector and accordingly increasing in height and depth between the upper and lower edge of the reflector. Such construction is open to the objection that the reflector becomes unduly heavy and ponderous owing to the increase in size and depth toward the outer edge. A further objection is that such prisms when exposed to heat contract and expand unequally to such an extent that the reflector is easily liable to fracture from that cause. A further objection to such reflectors is that the heaviest part of the reflector is at the outer edges of the same where the prisms are large, and the reflector is therefore not well balanced. Such reflectors are keenly sensitive to vibrations when suspended from brackets and electroliers.

By the use of my invention the prisms are broken up into a large number of small light weight prisms producing a well balanced reflector and one which contracts and expands equally under the action of heat thereby rendering it practically free from fracture from such a cause.

It should be understood that the prisms herein referred to are double-reflecting prisms the angles of which are generally in the neighborhood of the 90°.

By breaking up the prismatic surface of the reflector into dissimilar shaped prisms, but having a common double-reflecting power or forming the same into a plurality of panels for that purpose a reflector is produced having all the herein described advantages of construction and efficiency.

It is not essential that all of the prisms be double-reflecting in character as some of them may be curved and some diffusing and transmitting prisms.

I claim:

1. A reflector having upon its outer surface a series of radial double reflecting prisms extending from the top to the bottom thereof and of substantially uniform width throughout their length.

2. A reflector having its outer surface covered with radially extending double reflecting prisms, certain of said prisms being of uniform width and extending from the top to the bottom of said reflector, and other

prisms filling the spaces between the aforementioned prisms.

3. A reflector having upon its outer surface a series of parallel double reflecting prisms, certain of said prisms extending from the top to the bottom of said reflector.
4. A reflector having thereon a series of double-reflecting prisms of uniform width

throughout their length, and other series of ribs disposed angularly thereto.

In testimony whereof I affix my signature in presence of two witnesses.

OTIS A. MYGATT.
